UNITED STATES PATENT OFFICE.

ORRIN W. BRICKER, OF CLEVELAND, OHIO, ASSIGNEE, BY MESNE ASSIGNMENTS, TO THE OHIO BRASS COMPANY, OF MANSFIELD, OHIO, A CORPORATION OF NEW JERSEY.

RAIL-BOND STRAIGHTENER.

Application filed September 4, 1925. Serial No. 54,481.

My invention is an improvement in bond straighteners for use in straightening rail bonds and the like which in the course of manufacture become out of alignment due to strains released in the strands of the bond. Stranded rail bonds having their ends bound together with clips or the like have a tendency to become twisted during the course of manufacture. Considerable difficulty is often encountered when it is desired to weld such twisted bonds to a rail, since the clipped ends will not seat flush against the rail surface. This is especially true of stranded bonds wherein the strands are wormed about each other or assume an irregular path from one end of the bond to the other.

It is an object of my invention, therefore, to overcome such difficulties by providing an apparatus whereby such bonds may be straightened prior to welding to a rail so that the bond ends will seat flatly against the rail surface.

Another object of my invention is to construct a bond straightener which may be used to quickly and easily straighten bonds and the like in more than one plane.

Another object of my invention is to construct such a device whereby the ends of bonds and the like may be clamped and twisted or otherwise be maneuvered to place the bond in condition to be attached to a rail and to provide means for indicating when such condition has been attained.

Another object of my invention is to construct a device for straightening bonds whereby the bond ends will be placed in a condition to seat more perfectly within a welding mold for a cast welding operation.

Other objects and advantages of my invention will become apparent as a description of an embodiment thereof progresses, reference being had to the accompanying drawings in which like characters are employed to designate like parts throughout the same, and in which,

Fig. 1 is a front elevation of one form of my invention.

Fig. 2 is a side elevation of the same showing a rail bond clamped in place.

Fig. 3 is a plan view of the same, with one of the clamping members removed and showing the bond in place.

Fig. 4 is a view of a U-bond adapted to be straightened by my apparatus and showing

one of its ends tilted at an angle to the horizontal.

Fig. 5 is another view of the same bond showing one end bent inwardly.

Fig. 6 is a plan view of a second form of my invention showing means for straightening the bond in a plurality of planes.

Fig. 7 is a section on line 7—7 of Fig. 6.

Fig. 8 is a section on line 8—8 of Fig. 6.

Fig. 9 is a detail of one of the clamping members showing a bond end in position to be clamped, taken on line 9—9 of Fig. 6.

Fig. 10 is a detail on line 10—10 of Fig. 9, and

Fig. 11 is a view of a bond showing one end slightly twisted or in a condition usually found prior to placing in my apparatus.

In the drawings, Figs. 1 to 5 inclusive, illustrative of one embodiment of my invention, 1 represents a base on which the apparatus is mounted. Standards 2 and 3 are adjustably secured to the base 1 by bolts 4 which pass through slots 5 in the base.

Referring more particularly to Figs. 1 and 3, it will be seen that the standards 2 and 3 and respective various parts carried thereon are similar to each other.

Shafts 6 and 6' are rotatably supported in bearings formed in the standards 2 and 3 and 2' and 3' respectively, and are provided with collars 7 and 8 rotatable therewith on opposite sides of the standards 2 and 3 to prevent longitudinal movement of the shafts. Counter weights 9 and 10 are carried by the shafts 6 and 6' respectively and normally tend to rotate them toward each other. Operating or shaft oscillating handles 11 are secured to the collars 8 in any convenient manner and are preferably disposed radially opposite to the respective counter weights on the shaft.

Suitable indicating mechanism consisting preferably of indicator standards 12 and 13 rigidly secured to the rear standards 2' and 3' respectively, and terminating at their upper ends in turned over pointed portions 14 are provided to co-operate with the respective pointers 15 and 16 fixed to oscillate with the shafts 6 and 6' respectively. Movement of either of the shafts therefore from the zero or normal position in which the bond ends 17 and 18 of a bond 19 are desired to be brought when clamped in the device, will

100

105

be accurately indicated on either of the respective indicating mechanisms at 14-15 or 14-16. When the respective pointers are in alignment with the adjacent points 14, as shown in solid lines in Fig. 1 this indicates that the bond ends held within the clamping mechanism are in the desired planes (for welding or otherwise securing to a rail).

Referring now to the clamping mechanism, 10 20 and 21 indicates the body portions thereof which are similar and are preferably shaped as shown in the drawings to form vise like structures comprising spaced jaw members 22 and 23. These clamping members are rigidly secured to the forward ends of shafts 6 and 6' respectively to rock therewith.

Each clamp is provided with a removable bond seat plate as indicated at 25 which may 20 be secured to the lower jaw 23 of the clamp by means of screws or the like, 26. Each clamping plate 25 is provided with a recess 27 in its bond seating face to seat the bond end therein and to assist in more firmly 25 holding the bond end against lateral movement within the clamp during the straightening operation.

Pivotedly mounted within a recess 28 in the upper jaw 22 of each clamp is a plate 30 which is provided with plane lower and upper surfaces for engagement with the clip 30 on the bond end and the cam member 31 respectively. A compression spring 32 seated within a recess in the clamp body 35 exerts its force upwardly against the under side of the plate 29 to normally project the plate upwardly free of the bond end, when the cam member 31 is in non-clamping position.

40 The cam member 31 is rotatably and eccentrically mounted within the forked upper jaw 22 and rotates about a pin 33. A handle 34 is provided to rock the cam about its axis and into and out of contacting position 45 with the plate 29. It will be noted that when I am straightening bonds of the type shown in the drawings having clips on their ends are provided with ribs 35, the rib serves as a stop and abuts the end of plate 50 29 when the latter is formed against the bond end as shown in Fig. 2.

It will be understood that the clamping members as described above are substantially similar to each other and are each adapted 55 to securely hold the respective ends of a bond and I have consequently described only one of the clamping members, like characters representing like parts of both clamps.

Figs. 4 and 5 show a U-bond before it is 60 straightened wherein the ends thereof are provided with ribbed clips 30.

I will now describe the operation of the device shown in Figs. 1 to 5 which is more particularly adapted to straightening rail bonds of substantial U-shape as shown in

Figs. 4 and 5, although the apparatus is not limited to such use as it is obvious that bonds of other shapes may be used with this form of my apparatus.

The bond ends are preferably provided 70 with ribbed clips as already described. The bond ends are placed in the clamping devices indicated generally at 20 and 21, so that their flat surface rests upon the flat surface of the plates 25. The handles 34 are 75 rocked forwardly to cause the cams to move the plates downwardly into engagement with the clipped upper surface. It will be noted that the rib 35 abuts the edge of the plate 29 and limits the movement of the bond end 80 into the recess 27. When the bond ends have been clamped into position the operator takes one handle 11 in each hand and by oscillating the handles 11 of the shafts 6 and 6' either simultaneously or independently, according to the condition of the bond ends, when placed in the apparatus, causes 85 the ends to be twisted back and forth several times. The handles are then brought to rest at a point where the respective pointers 15 and 16 come to rest directly in line with the respective points 14. In such position the bond ends will be found to be 90 parallel and in the desired position to be welded or otherwise secured to a rail. The bond may be removed from the apparatus by 95 lifting the handles 34 releasing the bond ends.

In Figs. 6 to 11 inclusive, I have illustrated another embodiment of my invention. 100 In this embodiment, I provide a base 40 on which are mounted clamp supporting standards 41 and 42 and 43 and 44. The standards 41 and 42 are preferably adjustably mounted on the base by means of bolts 42 passing through the elongated slots 8 of the base.

105 Rockably supported by suitable trunnions 45 from bearings formed in the standards 41 and 42 and removable bearing blocks 46 is a clamp carrying base 47 provided at its rear with an upwardly and forwardly curved jaw member 48 removable.

An operating handle 49 is formed on the end of one of the trunnions 45 for rocking the clamp carrying base 47, while a pointer 50 is carried at the outer end of the other trunnion and is adapted to move to indicate the position of the base 47 on an indicating standard 51 which is rigidly secured to the 110 standard 42. The upper end of the member 51 is bent downwardly and terminates in a point 52, which, where in direct alignment with the point of the pointer 50, indicates that the base 47 is in a horizontal plane.

115 In Fig. 9, I have shown a detail view of the clamping device and the base 47 on which it is carried. The upper end of the jaw 48 terminates in a forked end 53 in which a cam 54 is rotatably supported on a 120

pin 55. A handle 56 is provided for rotating the cam. In this figure I have also shown the end of a rail bond 57 on which a clip 58 having a rib 59 is secured. The rail bond 57 is shown more clearly in Fig. 11. Referring again to Fig. 9, the end of the bond is adapted to rest with its flat side upon a plate or other plane surface 60 carried by the base 47.

10 Pivoted from the rigid jaw 48 at 61 is a clamping plate 62 having a recess 63 therein upon its lower or bond engaging face for engaging the rib 59 of the clip when the plate 62 is in clamped position to prevent longitudinal displacement of the bond end. A stop 63' is carried by the plate 60 to prevent transverse displacement of the bond end. The plate 62 is normally lifted above the rail bond end into engagement with the cam 54 by a spring 64. When the cam 54 is rotated by the handle 56 in one direction, its peripheral surface will force the plate downwardly to engage and clamp the bond end. Rocking of the handle 56 in the opposite direction will release the bond end and the spring 64 will return the plate 62 to its upper position.

Upon the standards 43 and 44 which are preferably fixedly mounted on the base 40 by bolts or the like, 70, I have provided a rockable clamp carrying frame 71, substantially U-shaped and having trunnions 72 upon which the frame is supported. These trunnions are supported in bearings formed in the standards 43 and 44 respectively, and detachable cover bearing blocks 73. One of the trunnions 72 carries a counter weight 74 supported from its outer end by a rod 75. The rod 75 may be adjustably mounted in the trunnion by a set screw 76. This counterweight makes for easier movement of the frame 71 and results in a more prompt straightening of the bond due to ease of operation.

45 A clamp supporting base 77 having a rigid forked jaw 78 similar to jaw 48 is rockable within the arms of the U-shaped frame 71, and is keyed to an end of an operating shaft 79 by pin 80. The shaft is rotatably mounted in the frame 71 and is provided with a handle 81 at its outer end. An indicating standard 82 is fixed to move with the jaw 78 and its upper end terminates in a point 83, while a pointer 84 secured to the frame 71 also terminates in a point 85. When the jaw 78 is in the position indicated in Figs. 6 and 7, the indicators 82 and 84 will be so positioned that the points 83 and 85 thereof will be in alignment. This indicator mechanism will indicate the degree of deviation of the bond end from the vertical while a similar mechanism consisting of a standard 86 rigidly secured to the standard 44, and a pointer 87 carried by one 50 of the trunnions 72 will indicate the de-

viation of the bond end from the horizontal.

The clamping device carried by the base 77 is similar to that carried by the base 47 and consists of a rigid forked jaw 78 carrying a cam 54 rotatably mounted therein at 55. A handle 56 is provided to rotate the cam 54 into bond engaging position. The bond end rests upon a plate 60 and is held in place thereon by a plate 62 pivoted at 61. The plate 62 is provided with a rib engaging recess 63, as shown, and is normally held in contact with the cam 54 by a spring 64.

75 It will be noted, that in this embodiment of my invention I have provided for straightening the bond and particularly the ends thereof, both with respect to the true vertical and horizontal planes, and that a bond subjected to the operation of my apparatus will have its ends brought into substantial alignment or in the desired position to flatly abut the rails, to which they are subsequently welded or otherwise secured.

80 The operation of this form of my invention consists in first adjusting the standards 41 and 42 to the desired position with respect to the fixed standards 43 and 44, then clamping the ends of the bond in the clamping devices. This is accomplished by placing the bond ends with their flat surfaces upon the plates 60, then pulling the handles 56 downwardly to cause the cams to force the plates 62 against the tension of the springs 64 and into contact with the upper surfaces of the bond ends. The bond ends are so positioned that the ribs 59 seat within the recesses 63 of the plates. As the handles are brought down under pressure the bond ends are clamped in place. Then the operator takes hold of the handle 49 with one hand and the handle 81 with the other. By imparting an oscillating movement to the handles either simultaneously or separately the bond ends are caused to be twisted in a vertical plane by the handle 49, and axially by the handle 81 when the latter is oscillated. The handle 81 and the clamping mechanism to which it is attached is also movable with the frame 71 about the trunnions 72 as an axis. Thus it will be seen that the clamping device mounted in the frame 71 is movable about two axes, whereas the clamping device carried by the standards is movable around but one axis. The counterweight 74 aids materially in manipulating the frame 71 about its axis and can be adjusted by means of the set screw to balance various loads carried by the frame, if desired. In order to determine when the bond ends have been brought into alignment or are in the desired position for welding, I have provided the indicating means previously described. When the handle 49 is operated, the pointer 50 being secured 85

70

75

85

90

115

120

125

130

to one of the trunnions 45 will move beneath the pointed end 52 of an indicator standard 51 as indicated by the arrows in Fig. 7. When the bond end is brought to the desired position the pointer 50 will be directly beneath the point 52 as shown in the figure. The operation of the other indicating devices is similar to that just described, the alignment of the respective indicator points indicating the desired position of the bond ends.

In operating my apparatus I have found that the handles 49 and 81 may be oscillated simultaneously in quick succession whereupon such bending of the bond ends causes them to heat up sufficiently to increase their bending qualities and also to aid in their retaining the desired position after the ends have cooled off. I have also found that the handle 49 after being oscillated in the manner described, may be held by the operator in position so that the indicator 50—51 remains in the desired position and when the points are in alignment. While the handle 49 is being held in such position, the handle 81 and the frame 71 may be rocked on their respective axes simultaneously or separately in quick succession heating up the other end of the rail bond. After this end is thus heated the handle 81 is brought into position so that the points 83 and 85 will be in alignment while the frame 71 is brought to rest so that the pointers 86 and 87 indicate the desired position. At the completion of this operation the bond ends may be released and the bond taken from the apparatus in a straightened condition.

It is to be understood that various changes may be made in this construction of my device without departing from the spirit of my invention or the scope of the subjoined claims.

What is claimed is:

45 1. In an apparatus of the class described, a base, standards carried thereby, one of said standards being adjustable, clamping devices carried by said standards for clamping the ends of a rail bond, each of said clamping devices being rockable as a unit on said standards and independent of each other, and separate means to rock each of said clamping devices.

55 2. In an apparatus of the class described, a base, standards carried thereby, one of said standards being adjustable, clamping devices carried by said standards for clamping the ends of a rail bond, each of said clamping devices being rockable as a unit on said standards, and means to rock said clamping devices, and indicating means movable with said clamping members for indicating the degree of inclination of said members.

65 3. In an apparatus of the class described,

a base, standards carried thereby, one of said standards being adjustable, clamping devices carried by said standards for clamping the ends of a rail bond, said clamping devices being rockable on said standards along substantially parallel axes, and means to rock said clamping devices, one of said clamping devices being also rockable about an axis at substantially right angles to said other axes.

4. In an apparatus of the class described, a base, standards carried thereby, one of said standards being adjustable, clamping devices carried by said standards for clamping the ends of a rail bond, said clamping devices being rockable on said standards along substantially parallel axes, and means to rock said clamping devices, one of said clamping devices being also rockable about an axis at substantially right angles to said other axes and indicating means movable about each of said parallel axes and said axis disposed at right angles to said parallel axes for indicating the degree of inclination of each of said clamping members.

5. In an apparatus of the class described, a base, standards carried thereby, one of said standards being adjustable, clamping devices carried by said standards for clamping the ends of a rail bond, each of said clamping devices being rockable as a unit on said standards and consisting of bond end supporting bases having recesses formed therein to seat said bond ends, clamping plates pivotally secured to said clamping devices and adapted to engage said bond ends, and clamping members adapted to engage said plates for securely holding said bond ends.

6. In an apparatus of the class described, a base, standards carried thereby, one of said standards being adjustable, clamping devices carried by said standards for clamping the ends of a rail bond, each of said clamping devices being rockable as a unit on said standards and consisting of bond end supporting bases having recesses formed therein to seat said bond ends, clamping plates pivotally secured to said clamping devices and adapted to engage said bond ends, and cams adapted to engage said plates for securely holding said bond ends.

7. In an apparatus of the class described, a base, standards carried thereby, one of said standards being adjustable, clamping devices carried by said standards for clamping the ends of a rail bond, one of said clamping devices being rockable about a single axis, and the other of said clamping devices being rockable about a plurality of axes.

8. In an apparatus of the class described, a base, standards carried thereby, one of said standards being adjustable, clamping devices carried by said standards for clamp-

ing the ends of a rail bond, one of said clamping devices being rockable about a single axis, and the other of said clamping devices being rockable about axes substantially at right angles to each other.

9. In an apparatus of the class described, a base, standards carried thereby, one of said standards being adjustable, clamping devices carried by said standards for clamping the ends of a rail bond, one of said clamping devices being rockable about axes substantially at right angles to each other, and indicating means operable by each of said clamping devices for indicating the degree of inclination of said bond end from the desired position.

10. In apparatus of the class described, a base, standards carried thereby, one of the standards being adjustable relative to the other standard, clamping devices to grip the ends of a rail bond being carried by said standards and rockable on said standards, one of said clamping devices being

independently rockable about two axes at right angles to each other to impart a torsional movement and a bending movement to the bond terminals, the clamping devices consisting of supporting bases and rotatable clamping members between which the bond ends are securely gripped to said clamping devices.

11. In an apparatus of the class described, a base, standards carried thereby, one of said standards being adjustable, clamping devices carried by the standards for clamping the ends of a rail bond, said clamping devices being independently rockable relative to each other about different axes angularly disposed to each other to impart to the bond ends either a torsional or a bending movement and independent means to rock said clamping devices independently of each other.

In testimony whereof I hereunto affix my signature this 1st day of September, 1925.

ORRIN W. BRICKER.
